UNITED STATES PATENT OFFICE.

MEADE WILDRICK, OF SAVANNAH, GEORGIA, ASSIGNOR, BY MESNE ASSIGNMENTS, TO THE SESAMEE COMPANY, OF HARTFORD, CONNECTICUT, A CORPORATION OF CONNECTICUT.

LOCK.

Application filed November 24, 1925. Serial No. 71,096.

This invention relates to improvements in locks, preferably of the keyless type, commonly designated permutation locks or combination locks. Such locks comprise, in general, a bolt or other locking element the effective movement of which, under certain desired circumstances, may be prevented by variably settable movement-obstructing elements or tumblers usually in the form of 5 permutation wheels, sometimes called combination wheels, which must be set in a predetermined relation to permit the bolt or locking element to be moved.

It is an object of the present invention to 15 provide a lock of the above described character in which the settable movement-obstructing elements herein referred to as tumblers are mounted in a housing which is movable with respect to the fixed portion of 20 the lock and which may be used as a manipulator for the bolt or locking element. Except when the tumblers have been set in a predetermined relation, movement of the connected 25 housing and locking element is prevented by stops mounted in or forming a part of the stationary or fixed portion of the lock and lying in the paths of movement of parts of the tumblers.

It is a further object of the invention to 30 provide means whereby the combination of the lock may be readily changed and to control the conditions under which a change of the combination may be effected.

Although, for purposes of illustration, the 35 invention has been disclosed in the form of a lock adapted to be applied to a box cover, packing case, or like article, the invention is one of general application, and, by making appropriate changes in the bolt or locking 40 member, may be used as a part of a lock of any desired character or as a part of any mechanism or apparatus in which it is desired to detachably connect two or more parts together or to temporarily prevent or 45 control relative movement between two or more parts.

In the drawings illustrating the preferred and one modified form of the invention—

Figure 1 is a face view of a lock embodying the invention in its preferred form.

Fig. 2 is a face view of the same lock

drawn to a larger scale, parts being broken away and parts being illustrated in section.

Fig. 3 is a view of the lock illustrated in Fig. 2, parts being shown in elevation and 55 parts in section along the line 3—3 of Fig. 2 viewed in the direction indicated by the arrows.

Fig. 4 is a view in cross-section taken along the line 4—4 of Fig. 2 and viewed in the 60 direction indicated by the arrows.

Fig. 5 is a side view of the lock drawn to a smaller scale than that of Figs. 2, 3 and 4, parts being shown in longitudinal section through the line 5—5 of Fig. 4 as viewed in 65 the direction indicated by the arrows.

Fig. 6 is a face view of the mounting member or stationary part of the lock, other parts being removed.

Fig. 7 is a detached face view of the rear 70 portion of the casing or housing in which the tumblers and associated mechanism are mounted.

Fig. 8 is a view in cross-section through the mounting member and tumbler housing, 75 the two parts of the housing and the mounting member being indicated as having been detached and slightly separated.

Fig. 9 is a view in perspective of a tumbler herein disclosed as a two-part permutation wheel, one part comprising a lock-controlling element and the other comprising a setting element.

Fig. 10 is a view, in longitudinal cross-section, of the lock disclosed in Fig. 2, the 85 locking element, tumblers and tumbler casing being indicated in the positions to which they are moved to render the lock ineffective.

Fig. 11 is a similar cross-sectional view of the lock, parts of the same being indicated as having been moved to positions which make it possible to vary the relations between the lock-controlling elements of the tumblers and the elements by which they are set whereby the combination of the lock may 90 be changed.

Fig. 12 is a face view of a modified form of lock, parts being shown in cross-section along the line 12—12 of Fig. 15, and parts being shown in cross-section along the line 100 12'—12' of Fig. 15, said parts being viewed in the direction indicated by the arrows.

Fig. 13 is a longitudinal sectional view of the lock illustrated in Fig. 12, the section being taken along the line 13—13 thereof and viewed in the direction indicated by the 5 arrows.

Fig. 14 is a view in cross-section through the mounting member or stationary part of the lock illustrated in Fig. 12.

Fig. 15 is a cross-sectional view of the assembled lock.

Fig. 16 is a side view of one of the permutation wheels of the lock illustrated in Fig. 12, said wheel being detached from the mechanism.

Referring first to Figs. 1 to 11 of the drawings, the preferred form of the invention is indicated as being embodied in a lock comprising a relatively stationary or fixed mounting element 30, a locking member 31 and a lock-controlling mechanism mounted in a tumbler housing or casing 32 (Fig. 4), the mounting element 30 being adapted for attachment to the box or other structure having parts to be locked, and the locking member 31 and housing 32 being so mounted therein as to be movable from a position in which the locking member is effective to a position in which it is ineffective.

The tumbler housing may, in order to facilitate assembling, be constructed in two parts herein disclosed as a rear box-like portion or casing 33 (Fig. 4) and an exposed face plate or cover-like portion 34, said parts being connected together by means of lugs 35 (Figs. 2, 4, 5 and 8), which may project from the rear surface of the face plate through slots 36 in the mounting member into direct engagement with opposed surfaces of attaching flanges 37 extending outwardly from the side walls of the rear portion of the housing. Separation of the front and rear portions of the housing may be prevented by fastening means of any appropriate character, such, for example, as screws 38 passing through openings 39 in the rear portion of the housing and having threaded engagement with holes 40 tapped in the lugs 35.

As clearly indicated in Figs. 1, 2 and 5, the length of the slots 36 exceeds the length of the lugs 35 by an amount equal to the desired movement of the locking member to provide for the movement of the housing with the locking member from its effective to its ineffective position.

The locking member 31 may be connected with the tumbler housing 32 in any desired manner, as by means of a shaft or bolt 41 which may be passed through a bracket 42 extending rearwardly from the under surface of the mounting element. In order to facilitate the assembling and detachment of the parts, the bracket 42 may be made separate from the face portion of the mounting element and may be secured thereto by

screws or other appropriate fastening means 43 passing through openings in the mounting element and having threaded engagement with holes tapped in the base portion of the bracket. If desired, the base portion of the bracket may be extended, as by means of flanges 44, to provide a more secure means of attachment between the bracket and the mounting element. The head of the locking member 31 may be detachably secured to a squared end portion 45 (Fig. 3) of the bolt 41 in any suitable manner, as by means of a pin 46.

The movement of the locking member 31 and connected parts from an effective locking position, as indicated in Figs. 2 and 3, to an ineffective position, as indicated in Fig. 10, may be controlled by the movement-obstructing elements or tumblers 47 (Fig. 2) mounted in the housing 32 and cooperating with stops 48 which may preferably comprise parts of the mounting element 30 or other fixed part of the lock structure, but might, if desired, constitute separately constructed elements, mounted or secured therein in any appropriate manner.

In the preferred form of the invention each of the tumblers 47 may comprise a lock-controlling element 49 and a setting element 50, the former of which may consist of a hub 51 provided with two outwardly-extending spaced flanges 52, 53, the latter to serve as a part of the means whereby the two elements of the tumbler may be coupled together, and the former to serve as a means cooperating with the stops 48 in controlling the movements of the locking member and connected parts.

The coupling of the two parts of each of the tumblers may be satisfactorily effected by means of one or more pins 54 projecting from one surface of the setting element 50 into engaging relation with one of a series of notched portions 55 in the flange 53, as clearly illustrated in Figs. 2 and 4.

When the parts of the lock are in their effective positions as indicated in Fig. 2, the stops 48 lie in the paths of movement of the abutments afforded by the flanges 52 and thereby prevent the shifting of the housing and connected locking member to unlocked position. Each of the flanges 52 is provided with a slot 56 which forms a clearanceway for the adjacent stop 48 when in registration therewith, thereby permitting the lock-controlling element of the tumbler to be moved to the left to the position indicated in Fig. 10.

To facilitate the setting of the tumblers in a predetermined relation such as to cause the slots in the flanges 52 to be brought into registration with the stops 48 and permit the lock-controlling element to be moved to its ineffective position, each of the setting elements 50, which may be mounted upon one

end of the hub of the adjacent lock-controlling element, is provided with a peripheral portion 57 accessible through a slot 58 in the face plate 34 of the housing 32 through which it may be manipulated. If desired, the rear wall of the housing may also be slotted, as at 59, and so positioned as to render the setting elements accessible for manipulation through the rear face of the lock as well as through the front face.

The peripheral portions of the setting elements may be sub-divided in any appropriate manner into a number of differentiated portions by means of which they may be moved to any desired position. The subdivisions of the periphery of the setting elements may be marked or modified in such manner that desired predetermined positions may be definitely identified either by appearance or by the sense of touch. Preferably, the periphery of each setting element will be divided into ten equal portions and numbered consecutively from "0" to "9."

In the form of the invention herein disclosed for purposes of illustration each of the setting elements is provided with oppositely-disposed laterally-extending offset portions 60, 61. As clearly indicated in Figs. 3 and 4, these portions are of such diameter that their outer peripheries are just clear of the inner and outer surfaces of the front and rear housing walls. They therefore serve as supports or strengthening elements such as would prevent the forcing of the walls of the housing inwardly along their central portions. These extended portions also serve as guards to prevent the insertion of thin wires or plates, or other "feelers", through the slots 58 in an attempt to pick the lock by locating the positions of the slots 56 in the abutment members 52.

Preferably, the tumblers will be provided with a brake or detent device of some sort intended to prevent accidental rotation of the tumblers and to yieldingly maintain them in any position in which they may be set. As herein disclosed, this feature of the invention comprises notches 62 in the peripheral portions of the setting elements and detent springs 63 (Fig. 4) which may be secured by means of screws or other suitable fastening devices 64 to the inner surface of the housing. Each of the detent springs is provided with a head 65 in such position as to be moved into engagement with each of the notches 62 as they are successively brought into registration therewith by the rotation of the tumblers.

If desired, some motive means may be provided normally tending to maintain the locking member and connected housing in the position in which the former is effective. As herein disclosed, this motive means comprises a spring 66 confined between the bracket 42 and the rear portion of the head

of the locking member, which is mounted for reciprocation in a guide 67 fixed or otherwise secured to the rear face of the mounting element.

As clearly illustrated in the accompanying drawings, the stops 48, abutment flanges 52 and adjacent parts of the mechanism may be so disposed as to provide clear passageways for the stops at each side of each of the abutments, as a result of which the tumblers may be moved out of set position when the locking member is in either its effective position or its ineffective position, as indicated in Figs. 2 and 10, respectively. When locked in the position illustrated in Fig. 10, so the effort of the spring to restore the lock to its effective position is overcome by the stops 48 which lie in the paths of movement of portions of the abutments. If, however, the permutation wheels are set in accordance with a predetermined combination, the slots 56 are all brought into registration with the stops 48 and the spring 66 immediately moves the locking member, with the parts connected thereto, to effective locking position.

To facilitate the changing of the combination, the setting elements 50 are journaled on the hubs of the lock-controlling elements 51 and means is provided whereby the respective elements of the tumblers may be separated by relative lateral movement so as to free the flanges 53 of the lock-controlling elements from their engaging relations with the pins 54 carried by the setting elements. One form of coupling disabling means, which has been included as a part of the present disclosure, comprises a ram or driving element 68 (Fig. 11) in threaded engagement with the inner end of the bolt 41. This driving element is provided with an operating shaft 69 passing lengthwise through the series of lock-controlling elements and forming a pintle therefor. The shaft may be detachably secured to the driving element in any appropriate manner, as by means of a threaded key 70 (Fig. 2), and an opening 71 may be provided in the bolt 41 in proper position to provide for the insertion and removal of the key. The opposite end of the shaft 69 may be provided with a manipulator 72 rotatably mounted in a bracket 73 extending rearwardly from the back face of the mounting element and having a knurled head 74 by means of which the shaft and attached driving element may be rotated.

When it is desired to change the combination at which the tumblers must be set to operate the locking mechanism, the driving element 68 may be moved from its normal position indicated in Fig. 2 to the position indicated in Fig. 11 by rotation of the manipulator 72. Such rotation causes the threaded driving head to be moved laterally

in the end of the bolt 41, thereby driving the series of lock-controlling members along the shaft 69 and separating the coupling elements of the tumblers, as indicated in Fig. 11. It will be observed that, if the lock is in the position indicated in Fig. 2, this operation can only be effected when the permutation wheels are in their set position, otherwise the separation of the parts of the tumblers will be prevented by the stops 48, which constitute fixed parts of the lock structure. These stops prevent movement of the abutments to the left, and movement of the setting elements and housing to the right is prevented by the engagement of the lugs 35 with the walls at the right-hand ends of the slots 36, as illustrated in Fig. 2. If, however, the tumblers have been set in accordance with the combination of the lock, the couplings may be disabled in the manner heretofore explained, and, with the parts of the lock in the positions illustrated in Fig. 11, the setting elements may be freely turned to any desired positions corresponding with a new combination while the lock-controlling elements are held fast by engagement between the slotted abutments 52 and the stops 48. After the combination has been changed, the parts of the lock are restored to their normal positions by rotation of the manipulator 72 and connected parts in the proper direction to advance the threaded driving element 68 from the position indicated in Fig. 11 back to the position indicated in Fig. 2.

In order that the coupling disabling mechanism may not be operated to effect a change of the combination when the locking mechanism is locked in the position in which the locking member is ineffective, additional locking means is provided to prevent such operation without first placing the tumblers in accordance with some predetermined combination. This feature of the invention, as herein disclosed, comprises a series of stops 75 extending from the inner surface of the tumbler housing into the paths of movement of the flanges 53, except when said flanges are turned into positions such as to bring extended slots 76, provided for such purpose in the flanges 53, into registration with the stops 75. If the slots 76 of any one of the flanges 53 is not in registration with the adjacent stop 75, relative lateral movement of the component elements of the tumblers is prevented, since the setting elements 50 are held within the housing because of their engaging relations with the slots 58 and 59, and movement of the lock-controlling elements to the left with respect to said housing is prevented by the contacting elements of the flanges and the stops 75.

From the foregoing description of the locking means which controls the operation of the coupling disabling mechanism it will

be apparent that, if it is desired to prevent meddlers from changing the combination at times when the coupling disabling mechanism is accessible, this may be effected by merely moving the parts of the lock to their ineffective positions and then turning the tumblers out of their set relation. In order to operate the coupling disabling mechanism it is then necessary to first reset the tumblers into a predetermined relation, which can be done only by one who has knowledge of the combination.

As clearly indicated in Fig. 1 of the drawings, the lock embodying the above described invention may be so constructed as to present an extremely neat and simple appearance. There is no requirement that such a lock be provided with anything in the nature of a projecting knob, hook or handle by which it may be operated. The face plate 34 of the housing 32, which projects slightly above the surface of the face plate of the mounting element 30, is adapted to serve as a manipulator which may be moved by the fingers when it is desired to shift the connected locking member 31 from its effective to its ineffective position. A device to which a lock embodying the invention is applied may, therefore, be unlocked by setting the permutation wheels, portions of which are exposed through slots spaced along the central portion of the face plate of the housing, after which the locking member may be released by a movement of the entire housing and its enclosed mechanism, using the face plate as a manipulator, as already described.

Any desired portions of the lock may be so constructed as to be separable from other portions in order to facilitate the assembling and dismantling of the same. If constructed in the manner herein indicated the lock may be readily assembled by first passing the end of the bolt 41 through the openings in the bracket 42 and guide 67. The rear portion of the housing may then be adjusted to its proper position with respect to the mounting element and the bracket 42 secured in place by inserting the fastening screws 43. The head of the locking member 31 may then be applied to the squared end 45 of the bolt 41 and secured thereto by inserting the pin 46, which may be of such diameter as to be maintained in place by frictional contact. The threaded head 68 of the coupling disabling mechanism may then be threaded into the opening provided therefor in the bolt 41, after which the component elements of the tumblers may be inserted through the opening in the mounting element and secured in place by means of the shaft 69 of the coupling disabling element, which may be passed endwise through the opening in the bracket 73 and the openings in the hubs of the lock-controlling elements to a position in which its right-hand

end is properly positioned within the opening in the driving element 68 to receive the key 70. This key may be inserted through the opening 71 provided therefor in the bolt 41 and the assembling of the lock may be completed by inserting the lugs 35 on the rear surface of the face plate 34 of the tumbler housing through the slots 36 provided therefor in the mounting element and then 10 securing the two parts of the housing together by use of the screws 38. It will be observed that all of the fastening elements of the lock are so disposed as to be inaccessible, except when the device to which the lock is applied is free to be opened.

In the modified form of the invention illustrated in Figs. 12 to 16, inclusive, parts corresponding with those of the preferred form illustrated in Figs. 2 to 11, inclusive, 20 are designated by like reference characters with primes added. This form differs from the first form described principally in that the lugs 48', which correspond to the stops 48, are carried by a support 77 of circular cross-section having squared ends 78 extending into recesses 79 provided therefor in the mounting element 30'. The ends of this support are firmly held in place without the aid of any direct securing means since they 25 are confined between the front and rear portions of the tumbler housing, one of which is secured to the other by means of the screws 38'.

Abutments 52', having the same function 35 as the abutments 52 of the preferred form of the invention, are provided by recessing the hubs of the permutation wheels 47' as at 80 and slotting the remaining portions as at 56' to provide clearanceways for the lugs 48' 40 during movement of the permutation wheels, tumbler housing and locking member from effective to ineffective position, and vice versa.

In the modified form of the invention the 45 tumblers are set and the parts of the lock operated to move the locking member from effective to ineffective position exactly as the corresponding parts of the preferred form are operated. Further description of the 50 modified form is therefore unnecessary.

The invention is not intended to be limited 55 in application to the specific forms herein disclosed for purposes of illustration but may include modifications and variations within the scope of the appended claims.

What is claimed is:

1. A lock comprising a mounting element, a locking element so mounted therein as to be movable from an effective to an ineffective 60 position and vice versa, a tumbler carrier connected with said locking element and movable therewith relative to said mounting element, independently settable tumblers mounted in said carrier, said tumblers having portions accessible for manipulation

through openings provided therefor in the face of said carrier, and stops fixed with respect to said mounting element and lying in the paths of movement of parts of said tumblers, thereby preventing effective movement of said locking element, except when said tumblers have been set in a predetermined relation. 70

2. A lock comprising a mounting element, a locking element so mounted therein as to be movable from an effective to an ineffective position and vice versa, a manipulator connected with said locking element and affording means whereby the latter may be moved from one of its two positions to the other, 75 permutation wheels mounted in said manipulator and having parts accessible through openings in its face whereby they may be set, and fixed stops extending from said mounting element into the paths of movement of parts of said wheels, thereby preventing effective movement of said locking element, except when said wheels have been set in a predetermined relation. 80

3. A lock comprising a mounting element, a latch so mounted therein as to be movable from an effective to an ineffective position and vice versa, motive means normally tending to hold said latch in its effective position and capable of returning it thereto after it 90 has been retracted, a manipulator connected with said latch and affording means whereby it may be retracted, permutation tumblers mounted in said manipulator, and fixed stops extending from said mounting element 95 into the paths of movement of parts of said tumblers, the movement-obstructing elements of said stops and tumblers being so disposed as to permit free movement of said latch from either of its two positions to the 100 other only when said tumblers have been set in a predetermined relation and to permit said tumblers to be moved out of such set relation when said latch is in either position.

4. A permutation lock comprising a plurality of permutation wheels each having a lock-controlling element and a setting element, couplings normally preventing relative rotation of said parts, a coupling disabling mechanism comprising two parts one 110 threaded into the other so as to be moved towards and from each other by relative rotation, and means through which the to and fro movements of said parts may be communicated to the parts of said couplings, 115 whereby on rotation of one of the parts of said disabling element in one direction the couplings may be rendered ineffective, thereby permitting said setting members to be rotated independently of the lock-controlling 120 elements to change the combination of the lock, and on rotation of said part in the opposite direction the effectiveness of said couplings may be restored. 125

5. A lock comprising a locking element 130

movable from an effective to an ineffective position and vice versa, a permutation mechanism to control the movements of said locking element, said mechanism comprising permutation wheels each having a setting element and a lock-controlling element including, as a part thereof, a circular slotted abutment, a set of stops to cooperate with said lock-controlling elements, connections between said locking element and said permutation mechanism whereby effective movement of the former is dependent upon relative translatory movement between said stops and said lock-controlling elements such as to cause said stops to pass through the slots in said abutments, said movement-controlling parts being so disposed as to prevent relative translatory movements except when said wheels are set in a predetermined relation with said slots and stops in registration, couplings normally preventing relative rotation between the parts of said permutation wheels, a coupling disabling mechanism comprising two parts one threaded into the other so as to be moved towards and from each other by relative rotation, and means through which the to and fro movements of said parts may be communicated to the parts of said couplings, whereby on rotation of one of the parts of said disabling mechanism the couplings may be rendered ineffective, thereby permitting the said setting elements to be rotated independently of the lock-controlling elements to change the combination of the lock, the stops and parts of said permutation wheels being so proportioned and disposed as to prevent coupling disabling movements of parts of said lock when said locking element is in its effective position except when said permutation wheels are in their set relation, thereby permitting said stops to enter the slots in the abutments on said lock-controlling elements, and thereby prevent rotary movement of the latter during the combination-changing movements of said setting elements.

6. A permutation lock comprising a plurality of permutation wheels each having a lock-controlling element and a setting element, couplings normally preventing rotation of one of the elements of each of said wheels with respect to the other element thereof but capable of being rendered ineffective as a result of axial movement of one of said elements relative to the other, a coupling disabling mechanism comprising two parts one threaded into the other so as to be moved towards and from each other by relative rotation, means through which the to and fro movements of said parts may be communicated to the elements of said permutation wheels whereby a rotation of one of the parts of said disabling mechanism may be caused to produce the relative axial

movements between the elements of said permutation wheels necessary to render said couplings ineffective, and locking means controlling the operation of said coupling disabling mechanism, comprising opposed elements obstructing the relative movements of its parts to render said couplings ineffective except when said permutation wheels have been set in a predetermined relation. 70

7. A permutation lock comprising a plurality of permutation wheels each having a lock-controlling element and a setting element, a supporting element for said wheels, couplings normally preventing rotation of one of the elements of each of said wheels with respect to the other element thereof but capable of being rendered ineffective as a result of axial movement of one of said elements relative to the other, a coupling disabling mechanism comprising two parts one threaded into the other so as to be moved towards and from each other by relative rotation, means through which the to and fro movements of said parts may be communicated to the elements of said permutation wheels whereby a rotation of one of the parts of said disabling mechanism may be caused to produce the relative axial movements between the elements of said permutation wheels necessary to render said couplings ineffective, and locking means controlling the operation of said coupling disabling mechanism comprising portions of the elements of said permutation wheels and opposed portions of their supporting element, said opposed portions being so disposed as to prevent such relative axial movements of the elements of said permutation wheels except when said wheels have been set in a predetermined relation. 90

8. A lock comprising a fixed mounting member, a movable lock-operating member, and a pair of cooperative movement-obstructing elements to control the movements of said lock-operating member, one of the elements of said pair having parts so disposed as to lie in the path of movement of a part of the other except when one of said elements is set in a predetermined position with respect to the other, the settable element of said pair being mounted in the movable operating member and being movable to its movement-obstructing position when said operating member is in either its effective or its ineffective position, and the other element being mounted in the fixed mounting member. 100

9. A lock comprising a fixed mounting member, a movable mounting member, a locking member controlled by said movable mounting member, and a permutation mechanism to control the movements of said movable mounting member, said mechanism comprising pairs of cooperative movement-obstructing elements, one of the elements of 110

each pair having parts so disposed as to lie in the path of movement of a part of the other except when one of said elements is set in a predetermined position with respect to 5 the other, the settable element of each pair being mounted in the movable mounting member, a portion of each being exposed for independent manipulation through an

opening in the face of said movable mounting member, and the other element of each 10 pair being mounted in the fixed mounting member.

In witness whereof, I have hereunto signed my name.

MEADE WILDRICK.
